(57) **CLAIM**

I claim the ornamental design for a fence post profile, as shown and described.

DESCRIPTION

FIG. 1 is a perspective view of a fence post profile showing my new design;

FIG. 2 is a front view of FIG. 1, the rear view being identical to the front view;

FIG. 3 is a side view of FIG. 1;

FIG. 4 is a top view of FIG. 1; and,

FIG. 5 is a bottom view of FIG. 1.

The fence post profile is broken in the center to indicate indefinite length.
